(57) **CLAIM**

The ornamental design for an RFID sticker, as shown and described.

DESCRIPTION

FIG. 1 is a top view of an RFID sticker showing my new design; and,

FIG. 2 is a front perspective view thereof.

The broken line portions of the figures are included to show unclaimed subject matter only and form no part of the claimed design.

1 Claim, 2 Drawing Sheets

FIG. 1

FIG. 2

UNITED STATES PATENT AND TRADEMARK OFFICE
CERTIFICATE OF CORRECTION

PATENT NO. : D695,278 S
APPLICATION NO. : 29/403382
DATED : December 10, 2013
INVENTOR(S) : Tuomas Koskelainen

Page 1 of 1

It is certified that error appears in the above-identified patent and that said Letters Patent is hereby corrected as shown below:

On the title page item (73), replace “UPM RFID OY, Pirkkala (FI)” WITH --Smartrac IP B.V.,
Amsterdam (NL)--

Signed and Sealed this
Fourteenth Day of April, 2015
